US00D900806S

(12) **United States Design Patent** (10) **Patent No.:** **US D900,806 S**
(45) **Date of Patent:** **** Nov. 3, 2020**

(54) **ELECTRONIC DEVICE**

- (71) Applicant: **LENOVO (BEIJING) CO., LTD.**,
Beijing (CN)
- (72) Inventors: **Jian Xu**, Beijing (CN); **Wenbo Shi**,
Beijing (CN); **Rong Gao**, Beijing (CN)
- (73) Assignee: **Lenovo (Beijing) Co., Ltd.**, Beijing
(CN)
- (**) Term: **15 Years**
- (21) Appl. No.: **29/588,990**
- (22) Filed: **Dec. 27, 2016**

Related U.S. Application Data

- (62) Division of application No. 29/459,556, filed on Jul.
1, 2013, now Pat. No. Des. 778,902.

(30) **Foreign Application Priority Data**

Dec. 31, 2012 (CN) 2012 3 0662968
Dec. 31, 2012 (CN) 2012 3 0662969
May 14, 2013 (CN) 2013 3 0177419

- (51) **LOC (12) Cl.** **14-02**

- (52) **U.S. Cl.**

USPC **D14/341**

(57) **CLAIM**

The ornamental design for an electronic device, as shown and described.

DESCRIPTION

FIG. 1 is a front view of an electronic device showing the new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a back, right side perspective view of the electronic device shown in an alternate configuration; and,

FIG. 8 is an enlarged view of the portion of the electronic device shown within the area designated as 8 in FIG. 6. The broken lines shown in the drawings depict portions of the electronic device that form no part of the claimed design.

1 Claim, 4 Drawing Sheets
